2 SHEETS-SHEET 2.

UNITED STATES PATENT OFFICE.

CHARLES J. NAUEN, OF PATERSON, NEW JERSEY.

NEEDLE-LOOM.

988,589.

Specification of Letters Patent.

Patented Apr. 4, 1911.

Application filed September 9, 1910. Serial No. 581,124.

To all whom it may concern:

Be it known that I, CHARLES J. NAUEN, a subject of the Emperor of Germany, residing in Paterson, Passaic county, and State 5 of New Jersey, have invented certain new and useful Improvements in Needle-Looms; and I do hereby declare the following to be a full, clear, and exact description of the invention, such as will enable others skilled 10 in the art to which it appertains to make and use the same, reference being had to the accompanying drawings, and to letters of reference marked thereon, which form a part of this specification.

15 This invention relates to looms of the so-called needle loom type and it consists in certain improvements therein having for their objects to simplify the construction and render the operations involved more certain and uniform and, in general, to provide a loom in which an improved quality of fabric may be woven without increasing the cost of manufacture.

20 The invention will be found fully illustrated in the accompanying drawings, wherein,

Figure 1 is a side elevation of sufficient of the improved loom to illustrate the present invention; Fig. 2 is a front elevation of the 25 batten structure and accessory mechanism; Fig. 3 is a vertical sectional view of the batten structure and accessory mechanism on a somewhat larger scale; Fig. 4 is a plan view of what appears in Fig. 3, certain parts 30 appearing in section; Figs. 5 and 6 are detail views of the means for actuating the upper and lower needles, respectively; and, Fig. 7 is a detail view of one of the needles.

35 In said drawings I have shown my invention applied to a loom of the narrow-ware type, that is, a loom in which a plurality of fabrics are woven at the same time; it will be understood, however, that my invention may be applied to looms of the kind in 40 which broad fabrics are woven.

45 *a* in the drawings represents the frame of the loom; *b* the batten carried by the pivoted lay-swords *c*; and *d* the crank-shaft 50 form which, through the wheels *e* and pit-men *f* connecting said wheels with the batten, the batten is caused to move back and forth, in the usual manner, to beat up the filling.

55 *g* is the breast-beam over a bar *h* on which the woven goods, *i* are drawn, being held

under tension, by suitable mechanism (not shown) and *h* the harness controlling the warps *i*.

Set in the top of the batten is a bar *j* movable therein longitudinally thereof. 60 One end of this bar has an opening *k* covered by a plate of leather or the like *l* having an orifice *m* to receive the upper end of the picker-stick *n* fulcrumed in the batten in the usual manner; the leather plate *l* 65 serves to deaden the shock of the picker-stick, reducing the noise and vibration incident thereto. To the back of the batten are secured the uprights *p* which are connected by a rod *q* having the bearing-pieces 70 *r* in which slides, parallel with the bar *j*, a bar *s*. To the bar *s*, at the end thereof opposite that adjoining the picker-stick *n*, is secured a block *t* having an orifice *u* which receives the upper end of a picker-stick *v* 75 fulcrumed in the batten structure. The block *t* is formed of leather so as to deaden the shock of the picker-stick. The plate *l* and the block *t* are secured to the bars *j* and *s* by screws *l'* and *t'* so that each may 80 be adjusted to right or left as the conditions may require. The picker-sticks are each normally drawn outwardly by the spring *o* in the usual manner. To the back of the batten is secured at each weaving space a 85 channeled rest *w* for the reed *x* which is held at the top, in the usual manner, by a clip *y* pivoted to the rod *q*.

At suitable intervals, corresponding to the center-to-center distance between each 90 two weaving spaces, upwardly projecting arms *z* are secured to the bar *j*, the same having in their upper ends (which are turned rearwardly) the horizontal needles 1, the point of each needle being projected to 95 toward the left and being provided with an eyelet 2 of porcelain or the like; the eyelet-carrying part of the needle is preferably a separable piece having a lap-joint connection with the body part, to which it is secured by the screw 3, so that it may be removed for renewing the eyelet or any similar purpose, (Fig. 7). At similar intervals downwardly projecting arms 4 are secured to the bar *s*, and in the lower ends of these 100 arms, in a plane slightly above the needles 1, are secured the needles 5, the same being identical in construction with the needles 1 and projecting from the arms 4 to the right. When the picker-sticks occupy the positions 110

shown in Fig. 2 all the needles 1 stand at the right and all the needles 5 at the left of the corresponding weaving spaces. The arms 4 are secured on the bar 8 by set-screws 6 so as to be adjustable on the bar (which is round in cross-section) forward and back to bring the needles in the desired relation to the needles 1.

The filling is supplied from a series of bobbins 7 carried by a support 8 beneath the batten. The filling from each bobbin passes upwardly therefrom through a tension-device 9, carried by the rail 10, and then through a vertical tube 11 penetrating the batten vertically at the back thereof, through the eyelet 2 of one of the needles (1, 5) to the cloth. The tension device 9 comprises a fixed member 12 and a pivoted member 13 having alternating eyelets 14 through which the filling passes zig zag fashion, the member 12 being held normally in the position shown by a spring 15.

In bearings 16 secured to the front upper edge of the batten is journaled a rock-shaft 17 carrying cranks 18 fixed thereto so as to be rotatably adjustable thereon by the set-screws 19 (each crank being immediately to the right of a weaving space) and also carrying cranks 20 which are pivotally movable thereon, being disposed between collars 21 and standing each immediately to the left of a weaving space. Each crank 18 (20) carries an adjustable arm 22 (22') which projects rearwardly over the batten and in its rear or free end is adjustably supported by the screw 23 an upright loop-holding needle 24 (24').

Below the crank shaft is journaled a shaft 25, the same being rotated from the crank-shaft through the transmission gearing 26. Tappet-cams 27 set oppositely to each other (and only one of which is shown) are arranged on this shaft and operate to depress alternately the levers 28 which are connected with the picker-sticks by the straps 29 extending over pulleys 30 arranged on the batten; the springs 30, which normally hold the picker-sticks in their outward positions, tend to raise the levers, which have sudden downward impulses imparted to them by the tappet cams resulting in quick movements of the picker-sticks inwardly and outwardly and consequently of the needles 1 and 5. On the shaft 25 are also fixed the reversely set cams 31 (one only being shown); each of these cams has one-half (approximately) of its periphery semi-circular, as at 32, while the remaining half includes a sudden depression 33, a concentric portion 34 and a rise 35 following in the order named in the direction of rotation of the cam as indicated by the arrow in Fig. 1. Against each of these cams an anti-friction roller 36 on one of two levers 37 is held by a spring 38 connecting the le-

ver with the frame. The cranks 18 and 20 which carry the loop-holding needles are caused to oscillate reversely, the motion being transmitted from the levers 37 as follows: At one end the rock-shaft 17 carries a rearwardly projecting arm 39 which is connected with the adjoining lever 37 by the adjustable pitman 40. In bearings 41 another rock-shaft 42 is journaled below the rock-shaft 17 and this rock-shaft carries cranks 43 which are connected with the cranks 20 by the links 44; at its right-hand end this rock-shaft carries a rearwardly projecting arm 45 which is connected with the corresponding lever 37 by the adjustable pitman 46. It is preferable to limit the upward movement of the arms 39 and 45 under the action of the springs 38 by stops 47 secured to the batten.

Operation: The batten is reciprocated in the usual manner from the crank-shaft d , the reed beating up the filling upon each forward movement of the batten and the shed opening on each backward movement thereof. On each backward movement of the batten, that is to say, while the shed is open, one or the other of the sets of needles carrying the filling (designated A) moves back and forth through the sheds, the movements of the two sets of needles alternating. Respecting either set of needles 1 and 5, as it reaches the limit of its movement into the shed the set of needles 24' (or 24) disposed at the relatively opposite sides of the fabrics is raised by a quick movement to catch the filling and, on the receding of the needles 1 or 5, coacts therewith to form the loops, the set of needles 24' (or 24) receding (descending) slowly so as to clear the loops which they are holding at about the time the batten advances to beat up the filling at the fell of the cloth. It will be understood, in view of the foregoing, that the sets of needles 24 and 24' alternately perform their up and down movements, so as to coact with the alternately moving sets of needles 1 and 5. To this end the shaft 25 rotates at one-half of the speed of the shaft d , the result of which is that every other time the batten moves back one or the other of the sets of needles 1 and 5 moves into and out of the sheds and that, during every other cycle of movement of the batten, one or the other of the sets of needles 24 or 24' quickly rises and slowly falls, the alternating movements referred to being due to the opposite relation of the cams 27 to each other and cams 31 to each other. The quick rise of either set of loop-holding needles 25, occurring as above stated, is due to the roller 36 acting on the corresponding cam 31 reaching the depression 33 in the cam, such rise being followed by a short dwell, due to the concentric portion 34 of the cam, and this dwell 130

being followed by the slow downward movement of the needles 24 (or 24'), due to the spiral portion 35 of the cam.

Having thus fully described my invention, what I claim as new and desire to secure by Letters Patent is:

1. In a needle loom, the combination of the frame, the batten, two filling carrying needles, oppositely movable separate supporting members for said needles each movable longitudinally of the batten, two upright loop-holding needles respectively coacting with the filling carrying needles, separate supporting members for the loop-holding needles journaled on the same axis parallel with the paths of movement of the needle supporting members, means for reciprocating the batten, means for alternately reciprocating the supporting members for the filling carrying needles and means for alternately oscillating the supporting members for the loop-holding needles, substantially as described.
2. In a loom, the combination of the

frame, the batten, filling carrying needles, two oppositely movable separate supporting members for said needles each movable longitudinally of the batten, two upright loop-holding needles respectively coacting with the filling carrying needles, a rock-shaft 30 journaled in the batten parallel with the paths of movement of said supporting members, a crank journaled on said shaft, supporting members for the loop-holding needles respectively carried by the rock-shaft 35 and crank, means for reciprocating the batten, means for alternately reciprocating the supporting members for the filling carrying needles and means for alternately oscillating the rock-shaft and said crank, substantially as described.

In testimony, that I claim the foregoing I have hereunto set my hand this 8th day of September, 1910.

CHARLES J. NAUEN.
